UNITED STATES PATENT OFFICE.

EDWARD HOLMES, BRITAIN HOLMES, AND EDWIN F. BEUGLER, OF BUFFALO, NEW YORK.

LOCK-CUTTING MACHINE FOR BARREL-HOOPS.

No. 904,480.

Specification of Letters Patent.

Patented Nov. 17, 1908.

Application filed May 29, 1902. Serial No. 109,455.

To all whom it may concern:

Be it known that we, EDWARD HOLMES, BRITAIN HOLMES, and EDWIN F. BEUGLER, citizens of the United States, residing at 5 Buffalo, in the county of Erie and State of New York, have invented certain new and useful Improvements in Lock-Cutting Machines for Barrel-Hoops, of which the following is a specification.

10 This invention relates to a machine for cutting locks on barrel hoops and the like which is automatically driven by power, the operator being merely required to feed the hoop blank into the machine where it is gripped and held while the cutters automatically cut the locks therein.

15 The main objects of the invention are to cut the locks automatically by machine power without the assistance of an operator.

20 One feature of the invention relates to the adjustability of the cutting devices so that the locks may be cut at different points.

25 The invention also relates to certain details of construction all of which will be fully and clearly hereinafter described and claimed reference being had to the accompanying drawings, in which,—

Figure 1 is a side elevation of the improved machine. Fig. 2 is a vertical longitudinal section on line *a a*, Fig. 3. Fig. 3 is a top plan view of the machine. Fig. 4 is an end elevation. Fig. 5 is a vertical transverse section on line *b b*, Fig. 3, looking in the direction of the arrow V. Fig. 6 is an enlarged detached 30 side view of one of the lock cutting mechanisms and its frame. Fig. 7 is an enlarged detached end view of one of the cutter frames with the lock cutting mechanism mounted therein. Fig. 8 is an enlarged detached 35 side view of the double cutter. Fig. 9 is an enlarged detached end view of the double cutter looking in the direction of the arrow W, Fig. 8. Fig. 10 is a top plan view of the cutter frame with the cutting mechanism removed. Fig. 11 is an enlarged detached 40 side view of one of the supports for the hooks. Fig. 12 is a detached side view of one of the lever stops also showing a section through the supporting bar. Fig. 13 is an enlarged detached end view of one of the 45 lever stops with a fragment of its supporting bar. Fig. 14 is an enlarged detached view of one of the cutter operating loops and its hook. Fig. 15 is an enlarged detached plan 50 view of the hook supports shown in Fig. 11.

Fig. 16 is an enlarged detached plan view of one of the weight supporting bars.

In referring to the drawings in detail, like numerals designate like parts.

The frame of the machine is preferably of 50 a rectangular form having a top bed 1, and vertical end parts 2. A horizontal longitudinally extending shaft 3, is journaled in the frame and is provided with a gear wheel 4, which meshes with a gear wheel 5, on a short 55 driving shaft 6, on which power transmitting pulleys 7, are mounted. A cross head or block 8, is mounted in slideways 9, in each of the end frame parts 2, so as to slide vertically therein and these two cross heads or 60 blocks are connected by a horizontal bar 10. A crank 11, is mounted at each end of the shaft 3, and has a crank pin 12, and connecting rods 13, each mounted at its respective 65 ends on the pin 12, and a pin 14, projecting laterally from one of the heads or blocks 8, serve to operatively connect the heads or 70 blocks to the shaft 3, so that the rotation of the shaft 3, will impart a vertical reciprocating movement to the blocks 8.

75 The lock cutting mechanism is operated from the horizontal connecting bar 10.

A cutter frame is mounted on the bed 1, near each end thereof, and one of these frames designated by the numeral 15, is fastened rigidly to the main machine frame and another designated by the numeral 16, is adjustable longitudinally so as to provide for 80 hoops of different lengths and for cutting locks at different distances apart.

90 A rock shaft 17, is supported in each frame between the opposed cone points 18, of screw bolts 19, see Fig. 7, and is slightly at an angle to the horizontal; one end of the rock shaft being in a slightly higher plane 95 than the opposite extreme substantially as shown in Fig. 7, to give the desired angle to the cutter blades 20, mounted on said rock shaft.

As the lock at one end of the hoop is cut 100 on the side opposite to which it is cut at the other end, the cutters are arranged to cut oppositely to each other, *i. e.* one cutter cuts downward to the right and the other cuts downward to the left.

105 It will be noted that two cutters are mounted on the rock shaft shown in Figs. 7, 8, and 9. The object of this is to cut two locks at one end of the hoop, the outer one of which weakens the wood so that the op- 110

erator can twist off the projecting end (which is provided as a convenient grasping portion for the operator) after locking the two extremes of the hoop together.

5 The shaft 17, is rocked by a loop device which loosely encircles the bar 10, and has connection to a lateral extension or crank projecting from the rock shaft. The preferred construction of the loop device is 10 shown in Fig. 14, in which a substantially U shaped portion 21, has its upper ends passed through and secured to a plate 22, by opposed lock nuts 23. A hook 24, has its lower extreme passed through and secured to 15 the plate by lock nuts 25, and is adapted to hook in an opening 26, formed in a lateral extension.

The cutters 20, and their supports are 20 formed preferably as shown in Figs. 8 and 9. A hub 27, is mounted on the rock shaft and is fastened against independent rotation by a set screw 28. Two lugs 29, and 30, project from the hub at substantially right angles to each other, see Fig. 8. A support 25 31, for the cutter blades 20, is secured to the substantially vertical lug 29, by a bolt 32, and is longitudinally adjustable to vary the position of the cutter blades.

The support is substantially of the same 30 hook form as the cutter and is provided with a shallow longitudinal groove indicated by dotted lines in Fig. 9, in which a central longitudinal rib 33, projecting from the lug 29, fits and slides to prevent lateral or twisting movement of the support.

The cutter blade 20, is adjustably fastened to the support 31, by a bolt 34, which passes through a slot 35, in the vertical portion of the blade, as shown in Fig. 8. 40 Usually however all of the adjustment necessary is obtained by moving the support 31, and the cutter block is locked to the support with its inner surface in close contact with the support to strengthen the same as shown 45 in Figs. 7 and 9.

An extension block 36, is secured to the approximately horizontal lug 30, by a screw bolt 37, and is provided with the opening 26, as before described, near its outer extreme 50 shown in Fig. 8, in which the hook 24, engages. The extension block 36, is longitudinally adjustable relatively to the lug 30, and has a shallow longitudinal groove 39, in which a longitudinal rib 40, projecting from 55 the side of the lug 30, engages and slides as shown in Fig. 9. An eye 41, projects from the hub to which the upper end of a spring 42, is secured. This spring automatically returns the cutter to its initial position after 60 the cutting is performed. The hoop when the lock is cut is placed in flat position on the bed and is held in place by a plurality of hooks 43. The stems 44, of the hooks fit and slide in vertical slideways 45, in supporting blocks 46, mounted on the bed and 65

formed substantially as shown in Figs. 11 and 15. Two of these slideways are also formed in the single cutter frame and three in the double cutter frame, see Fig. 3.

A horizontal bar 47, formed substantially as shown in Fig. 16, is placed on the lower end of each stem and serves as a support for weights 63, which pull the hooks down to grip the hoop by gravity. The bars 47, are secured to the stems by set screws 64. The 75 hooks are raised automatically by the elevation of the bar 10, which is vertically beneath the lower ends of the stems.

Plates 48 and 49, are mounted on the cutter frames, see Fig. 3, and are each provided 80 with curved depressions 50, for the passage of the cutters, the plate 48, having one depression and the plate 49, having two depressions to correspond to the number of cutters employed. The plates 48 and 49, are 85 also provided with openings for the passage of the stems of the holding hooks, see Fig. 2.

The double cutter frame is adjusted horizontally on the main machine frame to vary the distance between the two cutter frames 90 by a lever 51, which is pivoted to the rear of the machine frame and projects forward.

The lever is provided with a handle 52, at its forward end and a rod 53, is connected to an intermediate point on the lever and to 95 the double cutter frame so that a movement of the lever will adjust the cutter frame longitudinally.

A horizontal bar 54, is secured to the front of the frame and has a series of stops 55, 100 which serve to retain the lever in any position to which it may be adjusted, see Fig. 3.

The lever 51, has two downwardly extending pins 56, which are separated sufficiently to fit on opposite sides of a center upwardly 105 extending rib 57, formed on each stop 55, substantially as shown in Figs. 12 and 13, and thus hold the lever in its position. When it is desired to release the lever it is lifted sufficiently to disengage pins from the 110 rib.

The hoops are automatically kicked off of the machine bed after the locks are cut by a series of arms 58, which extend upward from a rock shaft 59, journaled in the machine 115 frame at one side of the shaft 3. The shaft 59, is rocked by a lateral lug 60, extending from the shaft 3, which strikes against a lug 61, extending from the shaft 59, after the cutters have operated and rocks the shaft 120 59, sufficiently to move the upper extreme of the arms 58, transversely across the machine and thereby throw the hoop off the bed. The arms 58, are automatically restored to their former position after a hoop is thrown off 125 by a spring 62.

The operation of the machine is as follows,—A hoop being placed in flat form on the bed, the holding hooks are drawn down by the weights and grip and hold the same 130

- and at the same time the cutters are operated by the depressing of the cross heads and cut the locks in the hoop. The cutters having operated the holding hooks move upward 5 and release the hoop and the removing arms move transversely across the bed and force the hoop off of the frame. Another hoop is now placed in position and the operation is repeated.
- 10 This improved machine is entirely automatic in its operation, the hoop blank being gripped automatically by power means, the locks cut automatically by the cutters and then automatically ejected from the machine.
- 15 All that the operator has to do is to feed the hoop blanks into the machine.
- The principal advantages of this machine reside in its simple construction, its automatic action and the cutting of all locks on 20 each hoop simultaneously.
- We claim as our invention.
1. In a machine of the character described, a frame, cross heads slidably mounted in said frame, a rod connecting said cross 25 heads, hoop lock cutting blades having support from the frame, a loop encircling the connecting rod and operatively attached to the lock cutting blades, a shaft and cranked connections between the shaft and cross 30 heads, substantially as set forth.
2. In a machine of the character described, a frame, cross heads slidably mounted in said frame, a rod connecting said cross heads, hoop lock cutting blades 35 having support from the frame, operating means connecting the rod and lock cutting blades, and means for reciprocating the cross heads, substantially as set forth.
3. In a machine of the character described, 40 a frame, cross heads slidably mounted in said frame, a rod connecting said cross heads, hoop lock cutting blades having support from the frame, operating means connecting the rod and lock cutting blades, 45 means for reciprocating the cross heads and a plurality of holding hooks having stems vertically above the connecting rod, substantially as set forth.
4. In a machine of the character described, 50 a frame, cross heads slidably mounted in said frame, a rod connecting said cross heads, a hoop lock cutter blade mounted on the frame near each end thereof and each blade being arranged to cut oppositely 55 to the other, and one of said blades being adjustable relatively to the other blade, operating means connecting the rod and cutting blades and means for reciprocating the cross heads, substantially as set forth.
- 60 5. In a machine of the character described a frame, a hoop lock cutter blade mounted on the frame near each end thereof and each blade being arranged to cut oppositely to
- the other, one of said blades being adjustable, a lever having operating connection to 65 said adjustable blade and means for locking said lever in its adjusted position.
6. In a machine of the character described, a frame, a hoop lock cutter blade mounted on the frame near each end thereof, one of 70 said blades being adjustable, a lever having operating connection to said adjustable blade, a bar attached to the frame and a series of stops attached to said bar.
7. In a power driven machine for cutting 75 locks in hoops, the combination of hoop holding mechanism, hoop lock cutting mechanism and hoop ejecting mechanism, all of said mechanisms being automatically operated by machine power, whereby the machine is entirely automatic in operation, the operator being merely required to feed the hoop blanks into the machine.
8. In a power driven machine for cutting locks in hoops, the combination of hoop 85 holding mechanism, hoop lock cutting mechanism, hoop ejecting mechanism, and automatic power driven means for operating all of said mechanisms in proper order whereby the machine is entirely automatic in opera- 90 tion.
9. In a machine of the character described, a frame, cross heads slidably mounted in said frame and connected to each other, hoop lock cutting blades having support from the 95 frame and operated from the cross heads and means for reciprocating the cross heads, substantially as set forth.
10. In a machine of the class described, a main frame, two cutter frames mounted on the 100 main frame and each carrying lock cutters, a plurality of hoop holding hooks, supporting blocks mounted on the main frame and having slideways for some of said hooks, and the cutter frames also having slideways for some 105 of said hooks, substantially as set forth.
11. In a machine of the class described, a frame having a rectangular top bed and vertical end parts, a horizontal longitudinally extending shaft journaled in said frame, a 110 cross head mounted in slideways in each of the end parts so as to slide vertically therein, a horizontal bar connecting said cross heads, a crank mounted at each end of the shaft, connections between the cranks and cross 115 heads, and lock cutting mechanism having operative connection to the horizontal bar connecting the cross heads, substantially as set forth.
